UNITED STATES PATENT OFFICE.

MYRON LEE KEITH, OF CAMPELLO, MASSACHUSETTS.

SOLE-CHANNELING MACHINE.

SPECIFICATION forming part of Letters Patent No. 448,436, dated March 17, 1891.

Application filed December 10, 1890. Serial No. 374,145. (No model.)

To all whom it may concern:

Be it known that I, MYRON LEE KEITH, of Campello, in the county of Plymouth and State of Massachusetts, have invented certain new and useful Improvements in Boot or Shoe Sole Channeling Machines, of which the following is a specification.

This invention has for its object to provide improved means for cutting a stitch-receiving channel in the bottom surface of the outer sole of a welted boot or shoe when said sole is in place on the boot or shoe and while the latter is on the last, the invention having for its chief object to enable the said channel to be cut in conformity to the outline of the sole after the latter has been fitted, thus securing absolute uniformity in the distance between the channel and the trimmed edge formed on the sole by the fitting operation.

By the term "fitting operation" I mean the operation of removing the surplus material from the edge of the sole after the sole has been applied to the boot or shoe.

The invention consists as a whole in a channeling-machine comprising a jack-holder adapted to support a last and a lasted boot or shoe thereon and to permit the revolution of said last about a center or axis and a channeling-tool mounted on a fixed support and movable thereon both vertically and horizontally, the said tool having a gage adapted to bear on the edge of the sole and determine the distance of the channel from said edge, the channeling-tool being movable in all directions required to enable it to conform to the curvatures of the edges and bottom of a sole, so that during the revolution of the last about the axis of the jack the tool will cut a channel extending entirely around the edge of the sole, the channeling operation being performed before the heel is attached.

The invention also consists in certain improvements relating to a machine organized as above indicated, all of which I will now proceed to describe and claim.

In the accompanying drawings, forming a part of this specification, Figure 1 represents a side elevation of a channeling-machine embodying my invention. Fig. 2 represents a perspective view of a portion of said machine. Fig. 3 represents a section on line 3, Fig. 1. Fig. 4 represents an enlarged view

of the channeling-tool and a part of its movable carrier. Fig. 5 represents a view of another side of the channeling-tool, showing the operation of a channel-opening device thereon. Fig. 6 represents an end elevation, and Fig. 7 a top view, of the machine, showing the jack and last in a position at right angles to that shown in Fig. 1. Fig. 6^a represents a modification, and Figs. 8 and 9 represent perspective views of different forms of channeling-tools.

The same letters and figures of reference indicate the same parts in all of the views. 65

In the drawings, *a* represents the jack which supports the last *b* during the operation of channeling the outer sole *c* of a boot or shoe on said last. The jack may be of any suitable construction, and is here shown as composed of a curved bar pivoted at 2 to ears *d'* on a vertical shaft *d*, which is journaled in a bearing *e*, affixed to a base or support *f*. The jack is provided with a rest 3 to support the fore part of the last and with a spindle 5, 75 mounted on an adjustable block or standard 4 to enter the socket in the rear portion of the last. At one end of the jack is a roller 7, arranged to run on a track or support *g*, and above said roller is a handle 6, by which the 80 operator can move the jack about the shaft or axis *d*. The track *g* is attached by arms *g'* to the base or support *f*, and is preferably raised at its ends above its central portion, as shown in Figs. 1 and 6, so that when the toe portion 85 of the sole is being channeled the heel will be depressed, as shown in Fig. 6, for a purpose hereinafter explained.

i represents the channeling-knife, which is affixed to a slide or shank *i'*, adapted to move 90 horizontally in a socketed holder *j*. Said holder *j* is provided with a dovetail shank *j'*, fitted to move vertically in a guide in a slide *k*, which is movable horizontally in a direction at right angles to the movement of the 95 shank *i'* on a dovetail guide-bar *l*, said bar being supported by standards *l' l'*, affixed to the base *f*. The horizontal movements of the shank *i'* in the holder *j* permit the knife to move in and out to conform to the edge curvature of the sole *c*, while the vertical movements of the shank *j'* in the slide *k* permit the knife to move up and down in conformity to the bottom curvature of the sole. The hori-

zontal movements of the slide *k* upon the guide-bar *l* enable the knife to move along the edge of the sole in the direction of the length thereof when the sole is in the positions indicated by full and dotted lines in Fig. 1.

5 The shank *i'* is provided with a gage or rest *m*, which is adapted to bear on the edge of the sole, said gage being behind the knife *i* and determining the distance from the edge of the

10 sole of the cut made by said knife. The shank *i'* is pressed forward to hold the gage *m* with a yielding pressure against the edge of the sole by means of a weight *n*, which is connected by a cord *n'* with the shank *i'*, said

15 cord passing through a channel in the shank *j'* and over a pulley *o*, Fig. 3, in the holder *j*.

The gage or rest *m* is pivoted at *m'* to the shank *i'* and is engaged with the lower end

20 of a push-pin *p*, which pin extends upwardly through a hollow handle *q*, affixed to the shank *i'*, and is provided with a knob *p'* and with an adjustable nut or stop *p''* above said handle.

When the pin *p* is depressed, it de- 25 presses and at the same time swings back

the gage *m*, as shown in Fig. 4, thus increasing the distance between said gage and the knife and permitting the knife to cut the channel farther from the edge of the sole. The gage is normally held in the raised

30 position shown in Figs. 2, 3, and 6 by a spring *r*, Figs. 2 and 3, in the handle *q*. It is desirable to make the channel farther from the edge of the sole at the shank than at other portions of the sole, and the operator is en-

35 abled by depressing the pin *p* to cause the knife to move farther inward from the edge of the sole when the knife reaches the shank portion. The extent of the variation or inward deflection of the channel is determined

40 by the adjustable stop or nut *p''*, which limits the downward movement of the pin *p* by striking the handle *q*, and is engaged with a screw-thread on the pin, so that when rotated on the pin it is raised or lowered, as the case

45 may be. The knife is curved or beveled at its acting portion, so that it makes an undercut slot or channel in the sole, the channel being inclined inwardly from the edge of the sole, as shown in Fig. 4, this form being known to shoe

50 manufacturers as the "English" channel.

The form and construction of the knife may be variously modified.

In Figs. 3, 4, 5, and 6 I show a simple form of knife composed of a vertical tang *2'*, attached to the outer end of the shank *i'* by a screw *3'* and provided at its lower end with a beveled cutting-edge *4'*.

In Fig. 8 I show an inclined cutting-edge *4'*, which is a continuation of the tang *2'*, the latter being attached to a shank or holder in an inclined position. In this modification the back of the knife is provided with a lip *5'*, which acts to open the channel by raising the flap formed by the cutting-edge.

65 In Fig. 9 the tang *2'* is inclined, as in Fig. 8, and the cutting-edge *4'* is in the same plane as the tang; but the channel-opening device

is a lip formed on a separate piece *6'*, attached to the holder.

The knife shown in Figs. 3, 4, 5, and 6 has no channel-opening device, and when said knife is employed I make use of a channel-opener *t*, attached to the under side of the shank *i'* and formed at one end to enter the channel and open the same, as shown in Fig. 5.

In operating this machine I take a boot or shoe the outer sole of which has been temporarily secured to the upper by glue or cement and has been trimmed after its application to the boot or shoe, the form of the trimmed edge being determined by the edge of the inner sole and the portion of the upper covering said edge, as described in another application for Letters Patent of the United States for improvement in sole-edge-trimming machines filed by me concurrently with this application. Said boot or shoe being on the last, I secure it to the jack *a* in the manner shown, and then after moving the jack 90 and the channeling-knife to the positions shown in full lines in Fig. 1 I present the knife to the face of the sole and commence cutting the channel, the commencement being preferably at the rear portion of the shank. 95

The knife is moved by the operator in the direction indicated by the arrow in Fig. 1 until it reaches the side portion of the toe. At this point the jack is turned end for end on its axis, or, in other words, from the 100 full-line to the dotted-line position shown in Fig. 1. During this swinging movement the knife remains nearly at rest, the movement of the sole being nearly sufficient to cause the knife to cut the channel around 105 the toe. When the jack reaches the dotted-line position, the progressive motion of the knife is continued until it reaches the rear portion of the shank at a point opposite the point of beginning. This completes the 110 cutting of the channel, after which the knife is raised and moved forward until the channel-opener enters the channel, as shown in Fig. 5. The knife-supporting devices are then moved in the opposite direction 115 until the channel-opener reaches the side portion of the toe, when the operator swings the jack back to the full-line position, the channel-opener passing through the toe portion 120 of the channel during the swinging movement, and then moving back to the starting-point of the knife through the remaining portion of the channel. The inclination of the track *g* is such as that the heel portion of the sole is depressed when the channel is being cut in the toe, as shown in Fig. 6. The

125 object of this arrangement is to prevent the inclined knife from cutting too deeply or too nearly in a vertical direction in making the toe portion of the channel, the depression of the heel compensating for the inclination of

130 the toe portion of the face of the sole, so that the channel has the same form at the toe as at other portions. My invention is not lim-

ited, however, to the centrally-depressed track, and said track may be made of any other suitable form.

The several movements which the channeling-tool is permitted to make—viz., the horizontal movements adapting it to the edge curves of the sole, the vertical movements adapting it to the bottom curves of the sole, and the progressive movements along the fixed guide-bar adapting it to move along the edge of the sole—may be termed a "compound movement."

So far as I am aware I am the first to mount a channeling-tool upon a fixed guide or support, such as the bar *l*, so that it has the described compound movement, and I do not, therefore, limit myself to the described combination of devices which permit said movement, it being obvious that various other mechanical devices may be adopted to so connect the channeling-knife with the fixed guide or support as that it can move horizontally at right angles to said support as well as vertically while moving in the direction of the length of said support.

I find in practice that the improved jack herein shown and described may be used in connection with a channeling-tool held and presented to the sole wholly by the operator's hand, the described mechanism for supporting the channeling-tool being omitted. Hence I do not limit myself in all cases to the use of the knife supporting and guiding devices, although I regard an organized machine including both the jack and the knife supporting and guiding devices as preferable to the jack used with a loose channeling-tool held only by the operator's hand.

In Fig. 6^a I show the channeling-tool as it may be constructed to be held only by the operator's hand.

I claim—

1. A channeling knife or tool having a compound rectilinear movement, substantially as described, and provided with a rest or gage having a substantially flat outer end arranged to bear on the edge of an outer sole, whereby the knife is adapted to move progressively along a boot or shoe sole and to conform to the edge and bottom curves thereof, combined with a swinging jack adapted to support a lasted boot or shoe in different positions for the action of said tool upon the outer sole, as set forth.

2. The combination of a fixed support or guide, a slide engaged with said guide and adapted thereby to move horizontally in a rectilinear direction, a tool-holder engaged with vertical guides on said slide and thereby

adapted to move vertically, a tool-carrying shank engaged with horizontal guides arranged on said holder and extending in a direction at right angles to the movement of the slide, said shank being provided with a channeling-knife, and a swinging jack adapted to support a lasted upper in different positions for the action of said tool upon the outer sole, as set forth.

3. The combination of a fixed support or guide, a slide engaged with said guide and adapted thereby to move horizontally in a rectilinear direction, a tool-holder engaged with vertical guides on said slide and thereby adapted to move vertically, a tool-carrying shank engaged with horizontal guides arranged on said holder and extending in a direction at right angles to the movement of the slide, said shank being provided with a channeling-knife, a vertical axis or shaft journaled in a fixed bearing, a jack pivoted to said shaft and adapted to swing horizontally by the rotation of the shaft and vertically by its pivotal connection therewith, last-supporting devices on the jack, and a jack-supporting track depressed between its ends, whereby the heel portion of the last is depressed when the jack is in position to present the toe portion of an outer sole thereon to the channeling-tool, as set forth.

4. The combination of a fixed supporting-guide, a knife-carrying shank having a compound movement thereon, as described, and provided with a channeling-knife, a sole-edge rest or gage pivoted to said shank, a push-pin whereby the operator may depress and retract the said rest or gage, and a spring whereby the rest is normally raised and held at its forward position, as set forth.

5. The combination of a fixed supporting-guide, a jack mounted to swing on a shaft or pivot beside said guide and midway between the ends thereof, said jack being adapted to stand beside the guide with either side toward the guide, a slide *k*, adapted to move lengthwise on the guide, and a knife-carrying shank having a compound movement on said slide, whereby the knife is enabled while moving with the slide along a boot or shoe sole to conform to the edge and bottom curves of said sole, as set forth.

In testimony whereof I have signed my name to this specification, in the presence of two subscribing witnesses, this 29th day of November, A. D. 1890.

MYRON LEE KEITH.

Witnesses:
